AUTOMATIC FEED MECHANISMS

Ralph E. Price, Highfield, Md., assignor to
Landis Tool Co., Waynesboro, Pa.

Application January 7, 1949, Serial No. 69,711

5 Claims. (Cl. 51—2)

1

This invention relates to machine tools, particularly grinding machines and more particularly to feed mechanisms operable automatically in definite relation to the work traverse movement of the machine.

The machine for which this invention is intended has a feed mechanism consisting of a feedscrew moved axially by power for a rapid feed movement as well as power operated means for rotating a feedscrew for a slow feed movement. In order to effect automatic adjustment of the feedscrew at each end of the traverse movement, the power means, in this case a piston and cylinder operable through a rack and pinion, must be moved a slight but measured distance. It is also desirable that this movement be adjustable. We prefer to accomplish this by providing a fixed maximum volume of fluid for actuating the feed piston and throttling this supply in order to adjust the increment of feed. It is, therefore, an object of this invention to provide a shuttle valve operable in timed relation with the reversing mechanism of a grinding machine for causing incremental movement of a feed mechanism.

It is a further object to provide means for modifying the function of said shuttle valve by means of a selector valve which may be positioned to provide incremental feed at either or both ends of the traverse movement or to substitute a continuous feed movement in the absence of a traverse movement when said shuttle valve is rendered inoperative.

Figure 1 is a hydraulic diagram of the relative arrangement of parts necessary to carry out the object of the invention.

Figure 2 is a section through the selector valve showing the means for locating the valve in various positions.

Figure 3 is a longitudinal sectional elevation of the selector valve.

Figure 4 is a series of sections taken through the selector valve in various angular positions thereof.

While this invention relates to grinding machines, it is not limited to such apparatus but may be applied to any machines having comparable functions. Since the invention deals primarily with hydraulic apparatus, it is not considered necessary to include in the drawings details of machine structure. The drawings, therefore, have been limited to the apparatus essential to the operation of the invention.

The means for producing a traverse movement consists of a cylinder 10 in which a piston 11 is

2

slidably mounted with a double piston rod 12 extending from each end of said cylinder. Fluid under pressure is directed from a pump 15 through line 16, throttle valve 17 and line 18 to reversing valve 19 from which it is directed automatically to opposite ends of cylinder 10 through lines 20 and 21.

Said reversing valve may be shifted by fluid under pressure directed automatically to opposite ends thereof by pilot valve 25 which receives fluid under pressure from line 18 through line 26. Said pilot valve is shown as being actuated by means of a lever 27. Said fluid is directed automatically through lines 30 and 31 to opposite ends of valve 19. At the same time said fluid is directed automatically through lines 35 and 36 to opposite ends of an automatic feed valve 40. Valve 40 receives fluid under pressure from pump 15 through line 16, line 45, choke coil 46 and line 47. The purpose of said choke coil is to limit the flow of fluid to shuttle valve 53 and thus prevent too rapid operation thereof. Pressure in line 46 exceeds that in line 18 by the drop across throttle valve 17. Said fluid is directed alternately through lines 50 and 51 to opposite ends of cylinder 52 in which is slidably mounted a piston type shuttle valve 53. Auto feed valve 40 also directs fluid alternately from opposite ends of said shuttle valve through lines 60 and 61 to a selector valve 70, which will be described later. The pressure of the fluid supplied to cylinder 10 is determined by a fluid operated relief valve 75 of the type disclosed in Patent 2,456,431, granted December 14, 1948.

The portion of the feed mechanism with which we are concerned consists of a feedscrew 80 having gear teeth thereon engaging rack teeth 82 on piston rod 83. Said piston rod is attached to a piston 84 slidably mounted in cylinder 85. Further details of this feed mechanism may be found in Price Patent 2,313,479, issued March 9, 1943. Fluid under pressure for actuating said piston may be supplied from pump 15 through line 18 and line 90 to selector valve 70 and then through line 91 from said selector valve to the right-hand end of cylinder 85. Fluid may also be supplied to said selector valve from shuttle valve 53, as described above.

The selector valve consists of a housing 100 and a rotatable valve member 70 having a knob 102. Said valve member is hollow and has a throttle valve 105 in one end, which is adjustable by means of a knob 106. At the other end is a relief valve consisting of a ball 110 urged by spring 111 into closing engagement of said

valve member. Said valve is held against axial movement by a screw 115 engaging an annular slot 116 in the valve member. Said valve may be adjusted angularly to four different positions determined by four peripherally spaced slots or notches 120 into which a ball 121 is pressed by spring 122 to position said valve member. Said valve member is divided into four sections:

Section AA has an annular groove 125 connected to the hollow portion of the valve member by a radial passage 126. Section BB consists of two circumferential slots 130 and 131 on the valve member substantially at right angles to one another. Section CC consists of a passage 135 diametrically through the valve member and a second passage 136 radially of said valve member and at an angle to passage 135. Said section also has a circumferential slot 137. Section DD is similar to section AA in that it consists of a circumferential groove 140 connected to the hollow portion of the valve member by radial passage 141.

Operation

The operation of the traverse and reversing mechanism described herein is well known and need not be repeated here.

The operation of the feed mechanism is dependent upon the operation of the reversing mechanism modified by the setting of selector valve 70.

Regardless of the setting of valve 70, automatic feed valve 40 and shuttle valve 53 are actuated each time the reversing mechanism functions. Automatic feed valve 40 performs a double function: It directs fluid under pressure from high pressure line 47 automatically through lines 50 and 51 to opposite ends of shuttle valve 53. While valve 40 is directing the fluid under pressure from line 47 to one end or the other of valve 53, it is also directing the fluid discharged from the opposite end of said shuttle valve through lines 60 or 61 to selector valve 70. Whether the fluid thus directed to said selector valve is utilized to effect incremental movement of slow feed piston 84 is dependent upon the setting of said valve 70.

Valve 105 determines the magnitude of said increment. Said valve may be adjusted to permit the passage of any or all of the measured amount of fluid discharged by shuttle valve 53. When valve 105 is so adjusted that only a portion of this fluid is used to effect the feed movement, the unused fluid escapes through relief valve 110 and radial passage 126 in section AA of valve 70 from which it is discharged through line 90 into the low pressure line 18. Thus, the pressure at which fluid is supplied to said cylinder 85 from line 91 is the resultant of the pressure of spring 111 and the machine pressure in line 18.

Valve 70 may be set in any one of four angular positions. In the first of these, when the carriage drive piston 11 is reversed at the left-hand end of its movement, automatic feed valve 40 is in its right-hand position, and the discharge from the right-hand end of shuttle valve 53 passes through line 51, valve 40 and line 61 to radial passage 136 and section CC of valve 70. From passage 136, said fluid is conducted through throttle valve 105 and radial passage 141 in section DD of said valve to line 91 leading to the head end of feed cylinder 85.

When the movement of piston 11 is reversed at the right-hand end of its travel, valve 40 is in its left-hand position as shown in Figure 1. In this position the measured amount of fluid discharged

from the left-hand end of valve 53 through line 50, valve 40 and line 60 enters a circumferential slot 137 in section CC. Slot 137 in section CC is connected by a port 150 to a similar slot 130 in section BB. In the first position of valve 70, slot 130 is connected with an exhaust passage 153; and thus when piston 11 is reversed at the right-hand end of its travel, the measured amount of fluid discharged from shuttle valve 53 is exhausted and no feed impulse is given to the feed piston 84.

In the Number 2 position of valve 70, passage 135 in section CC is in line with both of the lines 60 and 61; and thus the measured quantity of fluid discharged from either end of shuttle valve 53 is directed through throttle valve 105, as described above, to the head end of said cylinder 85.

It might be well at this point to call attention to the fact that sections AA and DD of valve 70 function in the same manner regardless of the angular position of said valve.

In the Number 3 position of valve 70 neither of the lines 60 nor 61 is connected to supply fluid to the center passage of said valve. However, fluid from the machine pressure line 90 enters port 160 of section AA and BB through slot 131 in section BB to port 161 in section BB. Port 161 is connected with the center portion of the valve through passage 135, and thus a continuous supply of fluid may be directed through throttle valve 105 and line 91 to complete a continuous or plunge cut feeding movement of piston 84.

In the Number 4 position of valve 70, the measured quantity of fluid from the left end of shuttle valve 53 passes through line 50, valve 40 and line 60 to radial passage 136 in section CC of valve 70. From passage 136 said fluid is directed through throttle valve 105 and line 91 to the head end of said cylinder 85. This occurs when piston 11 is reversed at the right-hand end of its travel. When reversal occurs at the left-hand end of the piston movement, the measured amount of fluid from the right-hand end of valve 53 passes through line 51, valve 40 and line 61. Line 61 is connected to slot 137 in section CC. In this position of the valve, slot 137 is connected through port 161 to slot 130 in section BB. Slot 130 in the number four position of valve 70 connects port 161 with exhaust passage 153. Thus, actuation of the feed mechanism occurs only at the right-hand reversal.

I claim:

1. In a grinding machine having a work support and a grinding wheel support, means for effecting relative transverse and longitudinal movement between said supports, said transverse moving means comprising a feedscrew and nut, a hydraulic motor for rotating one of said members, a reversing mechanism for said longitudinal moving means, an automatic feed valve actuated by said reversing mechanism, a shuttle valve of fixed capacity in excess of maximum requirements actuated by said automatic feed valve for supplying a measured maximum quantity of fluid under pressure to said feedscrew operating motor at each reversal of said longitudinal moving means and a selector valve between said shuttle valve and said screw operating motor for preventing operation thereof at one or both ends of the movement of said longitudinal moving means, said selector valve having means for predetermining whether all or a portion of said measured quantity of fluid reaches said feedscrew operating motor, and a relief valve for

by-passing the unused portion of said measured quantity of fluid.

2. In a grinding machine having a work support and a grinding wheel support, means for effecting relative transverse and longitudinal movement between said supports, said transverse moving means comprising a feedscrew and nut, a hydraulic motor for rotating one of said members, a reversing mechanism for said longitudinal moving means, an automatic feed valve actuated by said reversing mechanism, a shuttle valve of fixed capacity in excess of maximum requirements actuated by said automatic feed valve for supplying a measured maximum quantity of fluid under pressure to said feedscrew operating motor at each reversal of the movement of said longitudinal moving means, a selector valve between said shuttle valve and said screw operating motor for preventing operation thereof at one or both ends of said longitudinal movement, and a restriction in the supply of fluid to said shuttle valve to limit the rate of movement thereof.

3. In a grinding machine having a work support and a grinding wheel support, means for effecting relative transverse and longitudinal movement between said supports, said transverse moving means comprising a feedscrew and nut, a hydraulic motor for rotating one of said members, a reversing mechanism for said longitudinal moving means, an automatic feed valve actuated by said reversing mechanism, a shuttle valve of fixed capacity in excess of maximum requirements actuated by said automatic feed valve for supplying a measured maximum quantity of fluid under pressure to said feedscrew operating motor at each reversal of said longitudinal moving means and a selector valve between said shuttle valve and said screw operating motor for preventing operation thereof at one or both ends of the movement of said longitudinal moving means, said selector valve having means for predetermining whether all or a portion of said measured quantity of fluid reaches said feedscrew operating motor, and a throttle valve in said selector valve for determining how much of the output of said shuttle valve is supplied to said feedscrew operating motor.

4. In a grinding machine having a work support and a grinding wheel support, means for effecting relative transverse and longitudinal movement between said supports, said transverse moving means comprising a feedscrew and nut,

a hydraulic motor for rotating one of said mechanisms, a reversing mechanism for said longitudinal moving means, an automatic feed valve actuated by said reversing mechanism, a shuttle valve of fixed capacity in excess of maximum requirements actuated by said automatic feed valve for supplying a measured maximum quantity of fluid under pressure to said feedscrew operating motor at each reversal of said longitudinal moving means, means including an adjustable restriction for directing a predetermined portion of the output of said shuttle valve to said feedscrew operating motor, and a selector valve between said shuttle valve and said screw operating motor for preventing operation thereof at one or both ends of the movement of said longitudinal moving means.

5. In a grinding machine having a work support and a grinding wheel support means for effecting relative transverse and longitudinal movement between said supports, said transverse moving means comprising a feedscrew and nut, a hydraulic motor for rotating one of said members, a reversing mechanism for said longitudinal moving means, an automatic feed valve actuated by said reversing mechanism, a shuttle valve of fixed capacity in excess of maximum requirements actuated by said automatic feed valve for supplying a measured maximum quantity of fluid under pressure to said feedscrew operating motor at each reversal of said longitudinal moving means and a selector valve between said shuttle valve and said screw operating motor for preventing operation thereof at one or both ends of the movement of said longitudinal moving means, said selector valve having means for predetermining whether all or a portion of said measured quantity of fluid reaches said feedscrew operating motor, and means for by-passing the fluid not used for said motor.
